UNITED STATES PATENT OFFICE.

GEORGE WHITMER, OF BREA, CALIFORNIA.

OVERSHOT FISHING-TOOL.

1,381,529.

Specification of Letters Patent. Patented June 14, 1921.

Application filed January 2, 1920. Serial No. 349,077.

To all whom it may concern:

Be it known that I, GEORGE WHITMER, a citizen of the United States, residing at Brea, in the county of Orange and State 5 of California, have invented new and useful Improvements in Overshot Fishing-Tools, of which the following is a specification.

This invention relates to apparatus for 10 use in the removal or recovery of parts of well apparatus, and has for its object to provide an improved overshot fishing tool, and the invention consists of the construction and details an embodiment of which is illustrated in the accompanying drawings and 15 described and claimed herein.

Figure 1 is a plan view of the improved tool.

Fig. 2 is a central longitudinal section on 20 line 2—2 of Fig. 1.

Fig. 3 is a sectional view showing the application of the tool.

The invention, in its illustrated embodiment, comprises an exterior and substantially 25 constructed sleeve or carrier 2, here shown as of cylindrical form, and having internal threads 3 at its upper end to be connected detachably to a line of tubing indicated at 4, Fig. 3, by which the carrier 2 is designed to be lowered down into the well casing to the desired height.

The lower end of the carrier shell 2 is externally threaded as at 5 and is adapted to be attached thereby to a skirt or bell-shaped member 6, Fig. 3, to facilitate the guiding of the tool in the well casing and also to facilitate the guiding of the device over which the carrier is to be moved into the bore 7 of the lower end of the shell 2, 30 this bore preferably having a downwardly and outwardly divergent mouth 8 for guiding purposes.

A particular feature of the present invention comprises a series of durable and yieldable dogs or gripping members arranged in a peculiar manner in the interior of the carrier shell 2 and such dogs are operative to spring around external shoulders or other projecting parts on the part in the well that 35 is to be withdrawn and that is fished for with the improved tool.

In the present case the gripping members or dogs consist of straight bars 10 preferably of spring steel the inner faces of which 40 may be concaved as at 11 so that when a series of the dogs 10 are arranged in given

positions around the interior face of the carrier 2 their upper ends form substantially an expandible ring as indicated in Fig. 1. These straight spring dogs or bars 10 are disposed longitudinally in the bore or chamber of the carrier and have their lower ends secured by bolts or other suitable means 12 to the wall of the carrier, such walls perforated as at 13 to receive the bolts or screws 65 the heads of which are readily accessible by a tool of suitable character that may be inserted into a countersink 14 provided about the head of each of the screws 12.

In order to secure the proper or desired 70 inclination of the series of straight bars 10 the portion of the surface against which these bars seat is turned conically, the conical surface converging upwardly as indicated at 15 in Fig. 2 and terminating as 75 indicated at a line 16 that is arbitrary and over which line the carrier 2 is provided with a cylindrical bore 17, although if desired this bore may assume a divergent contour from the line 16.

The base of the conical seat portion 15 intersects with an inwardly extending shoulder 18 terminating the upper end of the bore or mouth 7 of the carrier 2 and which shoulder 18 serves to carry a part of the 85 load and also to facilitate the assembling of the dogs or bars 10 in the carrier or shell 2; the lower ends of the dogs abutting against the said shoulder 18.

From the above it will be seen that the 90 dogs 10 being substantially straight in longitudinal structure may be inexpensively manufactured and readily assembled and that they are given the desired convergent relation by reason of the angular surface 15 95 against which they are held by their fastening screws 12. The upper ends of the several yielding dogs 10 are shown as terminating in a common diametrical plane at about the upper end of the carrier 2.

In use of the device the skirt or guide bell 6 is attached to the lower end of the carrier and the latter is attached to the adjacent end of the line of tubing or pipe 4 and is then lowered into the well to such 105 position as will be determined by the location of the part as the tubing T to be removed. Usually the tubing T is constructed of a series of sections united by coupling rings C, and when the carrier 2 has been 110 lowered to the desired degree the dogs 10 snap into engagement below the shoulder

formed by the bottom edge of one of the couplings C and then the fishing tube 4 together with its carrier 2 can be lifted by the usual draw works or other means and the grappled or interlocked part as the tube T will be lifted up from the well.

Various changes may be made without departing from the spirit of my invention as claimed.

10. I claim:

A fishing tool for wells comprising a device adapted to be suspended in a well, said

device having an interior convergent surface, bars of spring material mounted flat against said convergent surface at one end and secured thereto so that the free ends incline toward one another and are free to spring outwardly, the attaching means for said bars including bolts received through openings in said suspended device and threaded into said bars.

In testimony whereof I have signed my name to this specification.

GEORGE WHITMER.
